UNITED STATES PATENT OFFICE.

JOSEPH E. CORKER, OF FORT LEE, NEW JERSEY, ASSIGNOR TO PACKARD MOTOR CAR COMPANY, OF DETROIT, MICHIGAN, A CORPORATION OF MICHIGAN.

DESIGN FOR A RADIATOR-CAP ORNAMENT.

Application filed June 25, 1926. Serial No. 18,184. Term of patent 14 years.

To all whom it may concern:

Be it known that I, JOSEPH E. CORKER, a citizen of the United States of America, and a resident of Fort Lee, New Jersey, have invented a new and original Design for a Radiator-Cap Ornament, of which the following is a specification, reference being had to the annexed drawing, forming a part thereof.

In the accompanying drawing:

Fig. 1 is an elevation of one side of a

radiator cap ornament embodying my new design; and

Fig. 2 is an elevation of the opposite side of said ornament.

I claim:

The ornamental design for a radiator cap ornament, as shown.

In testimony whereof I have signed this specification.

JOSEPH E. CORKER.
